MOTOR VEHICLE

Application filed August 8, 1928. Serial No. 298,241.

This invention relates to motor vehicles for transporting mixed concrete from the point of supply of the ingredients of the concrete to the place where the concrete is to be used. The invention has for its principal objects to provide a simple and efficient mechanism for continuously stirring the concrete from the time it is loaded on the motor vehicle until it reaches its destination and is discharged from the vehicle, thereby preventing separation of the ingredients of the concrete thus transported; to provide mechanism for quickly and easily connecting the stirring mechanism to the driving mechanism of the vehicle, to facilitate the operation of emptying the container and to regulate the flow of the concrete therefrom and to utilize the stirring mechanism for use in forcing the concrete towards the discharge spout of the container during the operation of pouring the concrete therefrom.

The invention consists in providing a motor vehicle with a rotary side delivery container and mechanism operated by the propelling mechanism of said vehicle for stirring the concrete and for facilitating its discharge therefrom; and it also consists in the construction, combination and arrangement of parts hereinafter described and claimed.

In the accompanying drawings, which form part of the specification and wherein like symbols refer to like parts wherever they occur,

Fig. 1 is a plan view of a motor vehicle equipped with a rotary side delivery container and a stirring mechanism embodying my invention,

Fig. 2 is a side elevation of the left side of the vehicle,

Fig. 3 is a side elevation of the right side of the vehicle with the container in position to discharge the concrete therefrom,

Fig. 4 is a plan view of the vehicle showing the container removed,

Fig. 5 is a transverse cross-section taken on the line 5—5 of Fig. 2, showing the mechanism for rotating the container and the stirring mechanism,

Fig. 6 is a vertical cross-section through

the rear portion of the vehicle, showing the drive gearing for the stirring mechanism,

Fig. 7 is a vertical section on the line 7—7 in Fig. 4 showing the roller support for the middle portion of the container,

Fig. 8 is a fragmentary side view of the right side of the vehicle frame, showing the notched bracket which receives the end of the chain for preventing rotation of the container to discharge position,

Fig. 9 is a vertical cross section on the line 9—9 of Fig. 2 through the left side rail of the vehicle frame and the adjacent portion of the container, showing the stop for limiting the return movement of the container to filling position and,

Fig. 10 is a transverse cross-section through the lower portion of the container and the adjacent right side rail of the vehicle frame, showing the chain for preventing rotation of the container to discharge position.

Referring to the accompanying drawings, my invention is shown in connection with a motor vehicle comprising a chassis frame A supported on wheels B, an engine C supported on the forward end of said frame and having a driving shaft connection S through a change speed gear housing D with the differential driving gear housed within the rear axle housing E. The vehicle is provided with the usual cab F for the driver, the usual lever G for manipulating the transmission gearing and the usual clutch pedal for connecting the engine with and disconnecting it from the rear driving axle. The motor vehicle construction thus far described is well known and it is considered unnecessary to illustrate it in detail.

Located back of the driver's cab F above the chassis frame A of the motor vehicle is a horizontal shaft 1, which extends longitudinally of the vehicle at the longitudinal center line thereof and has its ends rotatably supported in bearings 2 provided therefor on the upper ends of pedestals 3 rigidly secured to said chassis frame. Located between the supporting pedestals 3 for the shaft 1 is a semi-cylindrical tank or container 4 adapted to receive the concrete mixture that is to be transported. The trough-like container 4 is

left open at its top, and its end walls are provided with bearings adapted to receive the shaft 1, whereby said container is rotatably supported on said shaft. The container is also supported intermediate its ends on a roller bearing 5 journaled in a bracket 6 fixed to a cross member 8 which extends from side rail to side rail of the chassis frame A of the vehicle. The right side wall of the container is provided, at a point substantially midway of its length, with a laterally projecting discharge spout or hopper 9 having converging side walls extending from the end of the container to the mouth of the discharge spout and having its bottom inclined upwardly and outwardly from the lower portion of said side wall of said container to the mouth of said discharge spout. This construction of rotary, right-hand, side delivery container permits the container to be readily discharged or emptied by rotating it in a direction that will cause its discharge spout to swing downwardly into a position which will permit the contents of the container to flow therefrom by gravity; it also permits the quantity of concrete discharged from the container to be regulated by varying the angular position of the discharge spout; and it also permits the concrete to be discharged into a form while driving the vehicle along the side thereof, thereby securing an even distribution of the concrete lengthwise of the form.

The left hand side of the container is weighted to cause the container to return to its normal or upright position after being rotated to discharge position; and the left rear corner of the container is provided with a suitable stop 4^a adapted to abut against the left side rail of the chassis frame and thus limit the return movement of said container. The container is rotated on its axis in a direction which will cause the discharge spout on the right side thereof to swing downwardly to discharge its contents by means of a cross shaft 10, which is journaled in bearings on the chassis frame A beneath the container and is provided at one end with a removable crank 11, whereby said shaft may be manually rotated. The other end of the shaft 10 is provided with a worm 12 which meshes with a worm gear 13 fixed to a shaft 14 having a pinion 15 fixed thereto which meshes with an arcuate rack 16 fixed to the curved bottom of the container. The worm 12 and worm gear 13 are preferably located within a suitable housing 17 mounted on the chassis frame A. Mounted for vertical swinging movement on the left-hand side rail of the chassis frame opposite the arcuate rack 16 on the curved bottom of the container is a pawl or ratchet 18 adapted to abut against the under sides of the teeth of said arcuate rack, said pawl 18 being held in engagement with said teeth by means of a coil spring 19. The pawl 18 may be disengaged from the teeth

of the rack 16 on the bottom of the container by means of a rock shaft 20 journaled on the left hand side rail of the chassis frame and provided at one end with a rock arm 20^a adapted to bear against the inner face of said pawl. The other end of the rock arm is also provided with a rock arm 20^a which is actuated to rock the rock rod by means of a push rod 21 which extends crosswise of the chassis frame beneath the container. The pawl 18 when engaged with the rack 16 acts as a brake or catch for preventing the discharge side of the container from swinging upward, but said pawl does not interfere with the movement of said container to discharge position. The stop 4^a on the container serves to limit the return movement thereof to filling position; while movement of said container to discharge position is prevented preferably by means of a chain 22, one end of which is permanently secured to the bottom of said container and the other end of which is detachably secured within a notch provided therefor in an upstanding bracket 23 secured to the right side rail of the chassis frame.

The concrete mixture contained within the container is continuously stirred or mixed, to prevent separation of the materials or ingredients thereof from the time the mixture is placed within the container to the time of its discharge therefrom, by means of a stirring device comprising two helically wound metal blades 24 mounted on the shaft 1 and rigidly secured thereto for rotation therewith preferably by means of radial arms or spokes 1^a fixed to said shaft. These spokes or radial arms 1^a also serve as paddles for aiding the helical blades in stirring or mixing the concrete. As shown in the drawing the blade at one end of the tank is wound in the form of a left-hand helix and the blade at the other end is wound in the form of a right-hand helix, whereby the two blades operate to force the concrete from the ends of the container towards the middle thereof and thus operate to secure a complete discharge of the concrete from the container.

The stirring or mixing device is rotated within the container by means of a suitable take-off box H attached to the transmission housing D and containing gears meshing with the continuous rotating gears of the transmission gearing. A continuous rotating shaft 25 projects from the take-off box H and has a clutch connection 26 with a shaft 30 journaled in gearings provided therefor on the inner face of the right side rail of the chassis frame and having a gear 28 fixed thereto meshing with a gear 29 fixed to the shaft 25. The clutch 26 is operated to connect the shaft 30 with the continuous rotating shaft 25 of the take-off box by means of a clutch shifter lever 31 operated by means of a hand lever 32 fixed to a cross shaft 27, and which extends upwardly through the

floor boards of the cab within easy reach of the driver. The shaft 30 which is rotatably supported on the right-hand side rail of the vehicle has a universal joint connection 33 with an inclined shaft section 34 whose rear end 5 has a universal joint connection 35 with one end of a short shaft section 30^a journaled on the chassis frame adjacent the rear end of the container. The rear end of the shaft section 10 50 is provided with a bevel gear 51 which meshes with a similar bevel gear 52 fixed to one end of the cross shaft 36 having a worm 37 thereon meshing with a worm gear 38 fixed on a shaft 39 located thereabove. The other 15 end of the worm gear shaft is provided with a pinion 40 which meshes with a large reducing gear 41 fixed to one end of the shaft 1 of the stirring mechanism. By this arrangement the stirring device may be operated from the transmission gearing when the 20 vehicle is in motion and when it is standing.

The hereinbefore described stirring or mixing device secures a thorough and continuous mixing of the ingredients of the concrete in the container by maintaining the ingredients in a state of continual agitation from the time the concrete is placed within the container until it is discharged therefrom. The mixing device serves also to 25 facilitate the discharge of the concrete from the tank by forcing it towards the discharge spout thereof. The location of the discharge spout at the side of the container makes it easy to properly position the truck 30 with reference to the forms or wheelbarrows; and the rate of discharge of the concrete from the tank may be varied, depending on angular position of the discharge spout, which is 35 prevented from returning to filling position 40 by the pawl 18. The spout is swung downwardly to obtain the desired rate of flow of the concrete by means of the cross shaft 10 and is returned to its normal position by releasing the pawl 18.

45 The driving mechanism for the stirring device is simple and efficient and can be readily connected with the driving mechanism of the vehicle to drive same when the vehicle is moving or standing by manipulating the 50 clutch.

While I prefer to mix the concrete before placing it in the container of the motor vehicle for transport and to use the stirring device for preventing separation of the ingredients of the concrete from the time they 55 are placed within the container until they are discharged therefrom, it might be desirable, in some instances, to place the ingredients within the container before mixing and use 60 the stirring device for initially mixing the ingredients and for maintaining such mixture during transportation.

What I claim is:

1. The combination with a motor vehicle 65 and the driving mechanism therefor of a con-

tainer mounted on said vehicle for rotation on an axis disposed longitudinally thereof, the container wall on the right side of the vehicle being provided substantially midway of the ends of the container with a laterally 70 projecting discharge spout, whereby said container is adapted to be rotated on its axis to swing the discharge spout downwardly and thereby discharge the contents of said container on the right side of said vehicle, and a 75 stirring device operatively connected with the driving mechanism of said vehicle and operating in the discharge position of said container to force the contents of said container from the ends thereof towards the discharge 80 spout thereof, the left side of said container being weighted to automatically return said container to its normal or upright position.

2. The combination with a motor vehicle and the driving mechanism therefor of a semi-cylindrical side delivery container mounted on said vehicle for rotation on an axis disposed longitudinally thereof, a stirring device located in said container and operatively connected with the driving mechanism thereof to be operated thereby, and means for rotating said container on its axis, said means comprising a worm cross-shaft journaled on said vehicle, a longitudinal shaft journaled on said vehicle and having a worm gear meshing with said worm shaft, a pinion fixed to said worm gear shaft, and an arcuate rack secured to the curved portion of said container and meshing with said pinion.

3. The combination with a motor vehicle and the driving mechanism therefor of a container mounted on said vehicle for rotation on an axis disposed longitudinally thereof, whereby said container is adapted for rotation on its axis to discharge its contents from a side thereof, means tending to return said container to upright position, a stirring device in said container and operatively connected with the driving mechanism of said vehicle, an arcuate rack fixed to said container, a pawl mounted on said vehicle and meshing with said rack for resisting rotation of said container to filling position, a spring for holding said pawl in yielding engagement with said rack, and means for disengaging 115 said pawl from said rack to permit said container to rotate to filling position, said means comprising a rock shaft mounted in said vehicle and having an arm disposed in abutting relation to said pawl.

4. The combination with a motor vehicle and the driving mechanism therefor of a shaft disposed longitudinally of said vehicle, bearings for supporting the ends of said shaft, a semi-cylindrical container rotatably supported on said shaft between the bearings therefor, means for rotating said container on said shaft to discharge its contents from a side thereof, a stirring device located in said container for rotation with said shaft, and con-

necting means between the driving mechanism of said vehicle and said stirring device comprising shafting operatively connected to the driving mechanism of the vehicle, gearing associated with said shafting, and a large reducing gear on said longitudinal shaft and meshing with said gearing.

5. The combination with a motor vehicle and the driving mechanism therefor of a
10 trough-shaped container mounted on said vehicle for rotation on an axis disposed longitudinally thereof, means for rotating said tank on its axis, and a stirring device located in said container and operatively connected
15 with the driving mechanism of said vehicle, and means for rotating said stirring device, said means comprising flexible shafting operatively connected at one end to the transmission gearing of the driving mechanism of
20 the vehicle and provided at its other end with a bevel gear, a worm shaft provided with a bevel gear meshing with the bevel gear of said flexible shafting, a reducing gear on the stirring device, a worm gear shaft disposed cross-
25 wise to said worm shaft, a worm gear on said worm gear shaft, and a pinion on said worm gear shaft meshing with said reducing gear.

Signed at St. Louis, Missouri, this 6 day of August, 1928.
